LIGHT EMITTING GAS DISCHARGE MATRIX DISPLAY PANEL

Richard A. Martel, Toledo, Ohio, Fred E. Mansur,
Temperance, Mich., and Larry J. Lohmann, Centerville,
and Gerald E. Wojcik, Toledo, Ohio, assignors to
Owens-Illinois, Inc., Toledo, Ohio

Continuation-in-part of design application Ser. No. 26,325,
Dec. 7, 1970, now Patent No. 231,359. This application
Dec. 14, 1973, Ser. No. 425,050

Term of patent 14 years

The term of this patent subsequent to Apr. 16, 1988,
has been disclaimed

Int. Cl. D14—02

U.S. Cl. D26—5 C

FIG. 1

FIG. 2

FIG. 3

FIG. 4

FIG. 1 is a front elevational view of a light emitting gas discharge matrix display panel embodying our new design, the rear being identical to the front shown, as viewed turned 90°;

FIG. 2 is a top plan view thereof, the bottom being the same as the top shown;

FIG. 3 is an elevational view taken from one side thereof, the opposite side being a mirror image of the side shown; and

FIG. 4 is an enlarged fragmentary front elevational view of one corner thereof.

This is a continuation-in-part of design application Ser. No. 26,325, filed Dec. 7, 1970, now Design Pat. No. D. 231,359, issued Apr. 16, 1974.

We claim:

The ornamental design for a light emitting gas discharge matrix display panel, as shown and described.
